ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC SWITCH MECHANISM.

Application filed July 23, 1921. Serial No. 487,164.

To all whom it may concern:

Be it known that I, ARVID H. NERO, a citizen of the United States of America, residing at New Britain, in the county of 5 Hartford and State of Connecticut, have invented certain new and useful Improvements in Electric Switch Mechanisms, of which the following is a specification.

My invention relates to electric switch mechanisms, and particularly to a switch mechanism for electric lamp sockets. The object of my invention is to further improve and simplify a switch mechanism of the general type shown in my copending application Serial No. 276,467, filed February 12, 1919.

In the accompanying drawing—

Fig. 1 is a broken side elevation of an electric lamp socket in which my invention is embodied in one form;

Fig. 2 is a vertical section therethrough on the line 2—2, Fig. 1; and

Figs. 3, 4, 5 and 6 comprise an exploded view of the insulating body and switch mechanism of the socket, the ratchet-spring and adjusting abutment being omitted; Fig. 3 being a top plan view of the upper button of the socket body, Fig. 4 a perspective of the chain rail and ratchet, Fig. 5 a perspective of the switch spindle, star plate, switch spring, switch bar and actuating cam, which form a convenient assembly unit, and Fig. 6 a perspective of the lower insulating button and associated parts.

In the embodiment of my invention illustrated, the switch is mounted in an electric lamp socket comprising the usual cap 7 and shell 8, with insulating lining 9. Within the casing are housed the insulating buttons 10 and 11 with the interposed switch mechanism, as well as the lamp-receiving terminals 12 and 13 mounted on the outer face of the button 11 and adapted to receive the plug base 14 of the lamp 15.

Spacing apart the buttons 10 and 11 are standards 16, 17 and 18, of which the first-mentioned carries the detachable chain bell 19, while the standards 17 and 18 are tapped to receive the binding screws 20 and 21, by 50 which the lead wires are connected to the switch. The standard 18 is carried down through a suitable groove in the side of the button 11 and is offset at its lower end and tapped to receive the screw 22 which passes 55 through the usual yoke piece 23 overlying

the base flange of the screw shell 13 so that a direct electrical connection between these parts is established.

The standard 17 has a foot piece 24 received in a suitable channel in the inner face of the button 11. Beneath the foot piece 24 is a projecting flange of the switch contact 25 arranged at one side of the switch chamber. Diametrically opposite the same is a second switch contact 26 formed of a piece of strap metal bent to shape and having its outer end passed through the hole 27 in the button 11 through the base 28 of the center contact 12 over which base it is angled and secured by soldering. The contacts 25 and 26 lie in the valleys of a hill and valley course for the switch bar 29. As will be noted, the hills 30 of the course are quite short and steep, and the contacts 25 and 26 are provided with lugs 31 which lie against the adjacent faces of diametrically opposite hills, upon which they are supported.

To travel the switch bar 29 on its hill and valley course, I provide a switch mechanism mounted on the spindle 32. As here indicated the lower end of the spindle is freely journaled in a well 33 formed in the bottom of the cup-shaped central depression 34, on the ledge surrounding which the hill and valley course is laid out. The upper end of the spindle is freely journaled in a bushing 35 of rectangular shape, freely seated in a similarly shaped depression 36 in the button 10, through which a hole 37 is opened to admit a screw driver to the slot 38 in the bushing, so that the latter may be forced from its seat and rotated to tension the ratchet spring 39. One end of the latter is engaged as usual in a hole in the bushing, while the other end is offset and engaged by a suitable abutment 40 struck from the ratchet plate 41. The latter is carried by the insulating segment 42 to the margin of which is secured the chain rail 43.

Cooperating with the dogs 44 of the ratchet plate, is a star plate 45 fast on the spindle 32. Below the star plate and suitably spaced therefrom is a cam disk 46, also fast on the spindle 32. Cam arms 47 and 48 offset from the periphery of the cam disk 46 enter marginal notches 49 in the switch bar 29, which is freely mounted on the spindle between the star plate 45 and the cam plate 46. Be-

110

tween the switch bar and the star plate is arranged a coil spring 50, held in compression by the rigid assembly of the star plate and cam plate 46 on the spindle. To lessen 5 friction between the cam arms 47 and 48 and the switch bar 29, I preferably bevel the notches 49 through which the cam arms pass, so that the beveled bearing surface 51 of the notch coincides with the pitch of 10 the cam arm. It will be observed that these elements form an assembly unit which may be readily handled and positioned between the buttons 10 and 11 on the assembly of the socket parts.

15 The operation of the switch will be readily understood. When an angular displacement is imparted to the ratchet plate 41 by the actuation of the bell chain 52, its dogs 44 engage the arms of the star plate 20 45 and impart a rotary motion thereto. Assuming the switch bar 29 to span the contacts 25 and 26, the rotary motion imparted to the star plate and cam 46 tends to carry the switch bar around therewith. The ad- 25 vance thereof on its course, however, is impeded by the upwardly angled flanges 31 of the contacts which lie against the sides of the diametrically opposite hills 30. The cam arms 47 and 48 of the disk 46 now serve to 30 lift the switch bar up the rise of the hill, during which rise the switch bar lags behind the cam disk 46. On reaching the crest of the hill, the switch bar crosses the top under the impelling action of the cam arms 35 47, which it frictionally engages under the now severely compressed spring 50. As it passes the crest of the hills, the spring 50 urges it downward into the succeeding valley. The incline of the hill, however, is 40 sharper than the incline of the cam arms 47 and 48. Consequently the switch bar rides down the inclines of the cam arms 47 and 48 and is thereby thrust quickly forward on its course, overtaking the cam disk 46 and being 45 halted by impingement against the inclines of the succeeding pair of hills 30. It accordingly rests in the intermediate valley at a point remote from the end of the contacts from which it has just parted. This action 50 is very important in securing a wide break for the switch and greatly increases its current-breaking capacity.

The present construction involves a simplification of that shown in my copending application above referred to, and constitutes an improvement of practical merit, the details of which may be somewhat modified, without departing from what I claim as my invention. The switch mechanism may be utilized in a device of any suitable sort, and is not necessarily associated with an electric lamp socket. 55

I claim as my invention:—

1. In an electric switch having a hill and valley course, a switch bar riding the course, 60 a cam plate arranged beneath and having cam arms upwardly offset for engagement with the switch bar and passing therethrough, a compression spring above and normally pressing the switch bar against the 70 cam plate, and means for actuating said cam plate to cause the cam arms of the latter to lift the switch bar with lagging action over the hills of the course, said compression spring causing said switch bar to ride down 75 the cam arms with overtaking action as the switch bar descends into the succeeding valley.

2. In an electric switch, an assembly unit comprising a rotary spindle, a cam plate 80 fast thereon, cam arms extending from said cam plate, a switch bar freely mounted on said spindle and engaged by said cam arms, said cam arms passing through the switch bar, a compression spring normally holding 85 said switch bar in engagement with the cam plate, and a ratchet drive member fast on the spindle and forming an abutment for said spring.

3. In an electric switch, a rotary switch 90 spindle, a ratchet star plate fast thereon, a cam plate fast thereon and spaced therefrom, said cam plate having offset cam arms extending through the switch bar and toward the star plate, a switch bar freely mounted on said spindle between said star and cam plates, and a compression spring between the star plate and switch bar to force the latter against the cam plate, substantially as described. 95 100

In testimony whereof I have signed my name to this specification.

ARVID H. NERO.
